UNITED STATES PATENT OFFICE.

FRANZ MARKGRAF, OF NEW YORK, N. Y., ASSIGNOR OF ONE-HALF TO
EDMUND PALTZ, OF SAME PLACE.

GLOVE-SEWING MACHINE.

SPECIFICATION forming part of Letters Patent No. 373,937, dated November 29, 1887.

Application filed August 11, 1886. Serial No. 210,595. (No model.)

To all whom it may concern:

Be it known that I, FRANZ MARKGRAF, of the city, county and State of New York, have invented certain new and useful Improvements 5 in Glove-Sewing Machines, of which the following is a specification.

This invention relates to an improved glove-sewing machine of that class in which the material to be sewed is passed through between 10 two intermittently-rotating cups or disks by which it is held and exposed to the action of the reciprocating needle or looper; and the invention consists, essentially, in the arrangement of the spring fingers and gage extending 15 across the disks back of the fingers, means for imparting positive step-by-step rotary motion to the outermost cup or disk, means for guiding and protecting the reciprocating needle, and of certain details of construction and combination of parts, which will be fully described hereinafter, and finally be pointed out in the 20 claims.

In the accompanying drawings, Figure 1 represents a plan of my improved glove-sewing machine, parts being broken out. Fig. 2 is a side elevation, partly in section. Fig. 3 is a vertical longitudinal section through the cups. Fig. 4 is a plan of the same, with the supporting-arm of the outer disk broken away. 25 Fig. 5 is a vertical transverse section on line $x-x$, Fig. 3; and Fig. 6 is a detail plan of a portion of the feed cups or disks, drawn on a larger scale.

Similar letters of reference indicate corresponding parts.

A represents the supporting-casing of my improved glove-sewing machine. The driving-shaft by which power is transmitted to the different working elements of the machine 30 passes transversely over the supporting-casing and actuates the different parts by any approved mechanism, such as are shown and described in glove-sewing machines of this class heretofore patented. At one end of the supporting-casing A are supported two feed cups or disks, C C', of which the shaft of the disk C is supported in a bracket-bearing, C². The disk C receives intermittent rotary motion by the usual pawl-and-ratchet device operated 45 from the driving-shaft, which are well known

and need no further description in this connection. The reciprocating needle-bar D and the looper E are also made of the usual construction and operated by the usual actuating mechanism in the manner well-known heretofore. 55 The other feed cup or disk, C', is supported on a curved arm, C³, that extends horizontally through the casing. This disk, in contradistinction to the feed-disks of glove-sewing machines heretofore in use, is not moved by frictional contact with the feed-disk C, but receives positive intermittent rotary motion by special mechanism, which is operated by the needle-bar D, and which consists, mainly, of a lever, G, that is fulcrumed to the fixed covering-disk C⁴ of the feed-cup C', and to a screw, C⁵, passing through the supporting-arm C³ of said disk. 60

The outer end of the lever G is provided with a hinged and spring-actuated pawl, g, 70 which engages teeth of a ratchet-wheel, g', formed at any part of the circumference on the feed-cup C'. The opposite upwardly-extending end of the lever G is pressed by a spring, g², against the arm g³, which arm is acted upon 75 by a beveled lug or projection, g⁵, attached to the needle-bar D. By the return motion of the reciprocating needle-bar the fulcrumed lever G is oscillated by the beveled lug g⁵, so that a forward motion is imparted by the pawl 80 g to the ratchet-wheel g' of the feed-cup C'. During the forward motion of the needle-bar the beveled lug clears the pivoted arm g³, and thereby causes, by means of the spring g², the oscillating of the lever G in opposite direction, 85 so as to move the pawl g over the teeth of the ratchet-wheel ready to engage the same at the next return motion of the reciprocating needle-bar.

I do not confine myself to the special construction shown for imparting positive intermittent rotary motion to the outer feed-cup, as any other suitable mechanism may be used for this purpose. The motion of the outer feed-cup, C', is so timed that it moves simultaneously with the inner feed-cup, and thereby feeds the leather to be sewed in a regular and reliable manner forward between the disks or cups. 90

To a curved arm, H, that extends from the 100

casing A over the feed-disk C at that side where the fabric to be sewed enters the feed-disk, is readily attached a socket, that carries a curved and pointed finger, H', which 5 extends over the point of tangential contact of the feed-disks, as shown clearly in Figs. 4 and 6. A second finger, H², of similar shape, is applied to a curved spring-arm, H³, on the plate C⁴ of the disk C'. These two fingers H' and H² are located immediately above and close to the circumference of the feed-disks C C', and serve for the purpose of pressing the edges of the leather or other fabric to be sewed closer together in the same manner as if they 15 were to be fed by the fingers of the hand. The edges of the leather are thereby held firmly in position for the action of the needle, which passes transversely through the fabric immediately below the fingers H' H². Above the 20 fingers, at some distance in front of the same, the arm H is provided with an adjustable gage, I, that extends across the space between the feed-disks, as shown in Figs. 4 and 6, and which serves for regulating the distance from 25 the edge at which the needle is to sew the fabric. By steadyng the gage higher or lower the free seam-stitch is formed farther from or nearer to the edge of the fabric, as required.

The needle d of the needle-bar is supported 30 in position, before and after the same has pierced the fabric, by suitable guides, of which one is formed in the top surface of the plate C⁴, and consists of the groove i. The other consists of the arm M, which is pivoted at M' to swing vertically, and is pressed upward by a spring, M², having one end fastened to a projection, N, on the front of the case and the other end below said arm M. The said arm is bent at right angles at its front end and provided with a groove, i', which is in line with the groove in the upper surface of the plate C⁴. From the front end of the projection N the arm O projects, which has its free end bent downward and forms a stop, preventing the 45 swinging arm M from being swung up too high by its spring. Said arm M must be lowered during the forward motion of the needle into the position shown in Fig. 3, which is accomplished by the laterally-extending pin i² of the 50 needle-bar, which engages the beveled flange or cam-edge i³ on the top of the swinging arm M, as shown in Fig. 3. The needle is thus guided so as to pierce the leather without vibrations or other irregularities.

55 As there is more or less danger of the end of the rocking looper E catching the needle during the time that the needle is not in the groove i on the plate C⁴, as the looper swings over the needle when the same is in the said 60 position, I have provided a device for pressing the needle down in said groove and preventing it from rising accidentally. This device consists of a right-angled arm, P, one shank of which is mounted to swing on the front of the casing A, the other shank being provided with a lateral projection, P', which 65 extends over the groove i. A spring, P², act-

ing on the arm, presses the same upward and against a pin, R, projecting laterally from the lug g⁵ on the end of the needle-bar and up over 70 the arm P. A spring-wire, S, is fastened on the upper end of that shank of the arm P extending toward the plate C⁴, and has its end flattened, the said shank being provided with a slight depression, S', for receiving the flattened end S² of the said wire. As the needle-bar moves forward, the pin R passes under the spring-wire S and raises the flattened end of the same. During the return movement of the needle-bar the pin R passes over and 80 presses on the spring-wire, and thereby presses the forwardly-projecting shank of the arm P down and presses the lateral projection P' upon the plate C⁴ and the needle, and thus confines the needle in its place and prevents 85 the looper from catching on the needle.

A portion of my improved glove sewing machine is the same as other machines, partly on the same principle, the essential features being, however, the fingers for holding the 90 leather or other fabric and gage for regulating the depth of the stitch from the edges, the positive motion imparted to the outer feed-cup which is necessary for overcoming the increased pressure exerted on the fabric by the 95 fingers, and the device for guiding and steady- 100 ing the motion of the needle.

Having thus described my invention, I claim as new and desire to secure by Letters Patent--

1. In a glove-sewing machine, the combination, with rotary feed-cups, of a fixed and 105 pointed finger on each cup, substantially as shown and described.

2. In a glove-sewing machine, the combination, with rotary feed-cups, of a fixed finger applied to one cup and a yielding finger applied to the other cup, both being located above and transversely to the path of the needle, substantially as set forth.

3. In a glove-sewing machine, the combination, with rotary feed-cups, of a fixed finger applied to one cup, a corresponding yielding finger applied to the other cup, and a gage extending transversely across the space between the cups at some distance back of the 115 fingers, substantially as set forth.

4. In a glove-sewing machine, the combination, with rotary feed-cups, of a fixed finger applied to one cup, a yielding finger applied to the other cup, and a transverse vertically-adjustable gage that is located at some distance back of the fingers, substantially as set forth.

5. In a glove-sewing machine, the combination of rotary feed-cups and mechanism for imparting to each cup positive rotary motion, a fixed curved and pointed finger applied to one cup, and a yielding finger on the other cup, so that a friction is exerted by the fingers on 120 the fabric, substantially as set forth.

6. The combination, in a glove-sewing machine, of rotary feed-cups, a reciprocating needle-bar carrying a needle, needle-guides ar-

ranged on each cup, and mechanism for operating the needle-bar, substantially as shown and described.

7. The combination, with a rotary feed-cup having a needle-guide, a reciprocating needle-bar, means for raising and lowering said needle-guide so as to move out of the way of the needle-bar, and a second rotary feed-cup having a fixed needle-guide, substantially as set forth.

8. In a glove-sewing machine, the combination, with rotary feed-cups having fingers for holding the fabric, a transverse gage for the same, and of a reciprocating needle-bar and a looper, substantially as set forth.

9. In a glove-sewing machine, the combination, with the rotary feed-cups and reciprocating needle, of a needle-presser operated from the needle-bar, substantially as shown and described.

10. In a glove-sewing machine, the combination, with the rotary feed-cups and reciprocating needle, of a needle-guide, a needle-bar,

a rocking arm provided in its free end with a laterally-extending projection extending over 25 the needle-guide, and a projection on the needle-bar for operating said arm, substantially as shown and described.

11. In a glove-sewing machine, the combination, with rotary feed-cups and a reciprocating needle, of a rocking arm provided on its free end with a lateral projection extending over the guide-groove for the needle, a spring-wire on the said rocking arm, the end of which wire is flattened, and a pin projecting from the reciprocating needle-bar and extending over the said rocking arm, substantially as shown and described.

In testimony that I claim the foregoing as my invention I have signed my name in presence of two subscribing witnesses.

FRANZ MARKGRAF.
